UNITED STATES PATENT OFFICE.

HENRY H. SESSIONS, OF CHICAGO, ILLINOIS, AND ALFRED P. DENNIS, OF NEW YORK, N. Y., ASSIGNORS TO THE STANDARD COUPLER COMPANY, OF NEW YORK, N. Y.

CAR-COUPLING.

SPECIFICATION forming part of Letters Patent No. 558,212, dated April 14, 1896.

Application filed February 18, 1896. Serial No. 579,757. (No model.)

To all whom it may concern:

Be it known that we, HENRY H. SESSIONS, of Chicago, in the county of Cook and State of Illinois, and ALFRED P. DENNIS, of New York, in the county of New York, State of New York, have invented certain new and useful Improvements in Car-Couplings; and we do hereby declare the following to be a full, clear, and exact description of the same, reference being had to the accompanying drawings, forming a part of this specification, and to the letters of reference marked thereon.

This invention relates to improvements in car-couplings, being particularly applicable to couplers employing horizontally-swinging knuckles—such, for instance, as couplers of the Dowling type. In couplers of this type difficulty is experienced in unlocking or releasing the knuckles to uncouple the cars when pressure or strain is on the knuckles, due either to the spring-buffers being in contact and having springs of sufficient strength to keep the inner faces of the knuckles in contact or to strains incident to the train service; and it is the object of the present invention to provide a secure locking device for the knuckles to reduce to the minimum friction in locking and unlocking the same, and consequently the power necessary to be applied to the platform lever or handle to accomplish this end, whereby not only may the couplers be released at any time, but very strong springs may be employed in the platform-buffers to hold the buffers or vestibule-framing together.

Referring to the accompanying drawings, Figure 1 is a side elevation of a coupler constructed in accordance with our present invention, a portion of one of the sides being broken out to illustrate the internal arrangement of the locking mechanism. Fig. 2 is a front end elevation of the same. Fig. 3 is a top plan view. Fig. 4 is a horizontal section. Fig. 5 is a detail elevation of the locking-pin and its operating-arm. Figs. 6 and 7 are sections on the lines *a* and *b*, Fig. 5. Fig. 8 illustrates the spring in top and side elevation.

Like letters of reference in the several figures indicate the same parts.

The coupler-head A, together with its draw-bar B and the knuckle C, pivotally mounted in the head to swing in a horizontal plane, are all of any ordinary construction, and as a matter of convenience we have illustrated a well-known form of device now on the market, in which the head is provided with curved ribs and recesses for receiving the corresponding ribs and recesses *c* in the knuckle, such ribs and recesses being struck in the arc of a circle and constituting the pivots about which the knuckle turns. The knuckle is provided, as usual, with an extension or wing D, which is adapted to coöperate with the locking mechanism, both to prevent the knuckle from being turned to uncoupled position as well as to prevent the same escaping entirely from the draw-head. This wing or extension D is struck on a center coincident with the axis of the knuckle, and it is adapted to intersect an aperture formed at right angles to its plane of movement or extending vertically through the draw-head and adapted to contain the locking mechanism, which in the present instance is a pin. This pin (lettered E in the drawings) is adapted to be rotated on its longitudinal axis to lock or release the knuckle instead of having a vertical movement, as is usual in this class of devices, and in order to effect the locking of the knuckle it is provided at a proper point in its length with a notch or segmental recess *e*, adapted when the pin is turned to one position to coincide with the arc described by the wing or extension D of the knuckle, but when the pin is turned to a different position a section of the body of the pin will be interposed in said arc and prevent the movement of the knuckle on its center. Such an arrangement presents a practically solid abutment, against which the wing or extension on the knuckle strikes and does not tend to turn the pin or release the knuckle under shock or strains incident to wear and tear in traffic.

In the preferred construction the end of the wing which comes against the lock or locking-pin to hold the knuckle in closed position is curved to correspond to the circumference of the pin, as shown at F, thereby

insuring a good wide bearing and overcom-
ing any liability of rupturing the wing itself
or breaking the locking-pin.

As a precaution against the entire escape
or release of the knuckle from the draw-
head, stop projections G are formed on the
rear end of the extension or wing D, which
stop projections, when the knuckle is fully
opened, are adapted to strike or contact with
the locking-pin above and below the seg-
mental notch therein, it being preferable to
form at these points on the locking-pin pro-
jections g, Fig. 7, against which the stops on
the knuckle will take a firm bearing to ar-
rest the knuckle in its outward movement.

As a convenient means for turning the pin
on its longitudinal axis we preferably pro-
vide a squared portion at the lower end, upon
which is fitted an operating-arm II, which
may be connected to the platform-lever in
any ordinary or preferred manner, and to
further secure the automatic locking of the
coupler when the knuckle is turned back a
spring is interposed between the pin and
draw-head tending to turn the pin into
locked position. This spring (lettered I in
the drawings, Fig. 8) is wound spirally
around the pin near the lower end, Fig. 1,
and has one of its ends set into a recess in
the draw-head and the other into a recess in
the lever, a series of recesses being provided,
if so desired, for adjusting the tension of
the spring in the ordinary way. The move-
ment of the pin on its axis may be limited by
a stop or stops cast on the bottom of the
draw-head—such, for instance, as illustrated
by the letter S, with which the handle comes
in contact.

The spring tending to turn the locking-pin
into locked position at all times will cause
the side or edge of the recess therein to ride
against the segmental circumference of the
wing or extension D during the time the
knuckle is open. Thus it forms in effect a
friction-lock for preventing the knuckle from
being jolted out of open position when it is
desired to couple the cars, and furthermore
as the knuckle is thrown to closed position
in the act of coupling, the pin is at once
turned in behind the wing or extension and
locks the parts firmly. To release the
knuckle, it is necessary to again positively
rotate the locking-pin on its longitudinal
axis, and while it is held in its open position
to separate the draw-heads, this act in itself
throwing the knuckle open, where it will re-
main, if so desired, until the cars are again
coupled.

Having thus described our invention, what
we claim as new is—

1. The combination with the draw-head
and the knuckle pivotally mounted therein
to swing in a horizontal plane and having
the locking wing or extension, of the locking-
pin journaled in the draw-head to rotate on
its longitudinal axis, and having the recess
therein, through which the locking wing or

extension passes when the knuckle is moved,
the pin forming an abutment in the same
horizontal plane as the notch against which
the locking wing or extension strikes to hold
the knuckle in locked or closed position; sub-
stantially as described.

2. The combination with the draw-head
having the aperture therethrough and the
knuckle journaled to rotate in said head in
a plane at right angles to said aperture and
having the locking wing or extension, of the
locking-pin journaled in an aperture in the
draw-head, held against longitudinal move-
ment and having the recess through which
the extension or wing on the knuckle passes,
the pin forming an abutment when turned in
front of said wing to lock the knuckle in
closed position; substantially as described.

3. The combination with the draw-head
having the aperture therethrough and the
knuckle journaled to turn in said draw-head
in a plane at right angles to the aperture and
having the segmental locking wing or exten-
sion, of the locking-pin journaled to rotate
on its longitudinal axis in the aperture, the
segmental notch in said pin through which
the segmental wing on the knuckle passes
when the knuckle is opened, the body of the
pin in the transverse plane of the notch form-
ing an abutment for coöperating with the
wing when the knuckle is closed to lock the
same in its closed position; substantially as
described.

4. The combination with the draw-head,
having the aperture therethrough and the
knuckle journaled in the draw-head to move
in a plane at right angles to the aperture and
having the locking wing or extension with
the stop projections thereon, of the locking-
pin journaled in the aperture to rotate on its
longitudinal axis and having the central
notch or recess through which the wing passes
as the knuckle is opened and the projections
above and below said recess with which the
stop projections on the wing coöperate to
limit the outward swing of the knuckle, the
body of the pin in the transverse plane of the
notch constituting an abutment for holding
the knuckle in locked position; substantially
as described.

5. The combination with the draw-head
having the aperture therein and the knuckle
journaled in said draw-head to move in a
plane at right angles to the aperture and hav-
ing the wing or extension, of the locking-pin
having the notch or recess through which the
wing passes when the knuckle is opened, the
body of the pin in the transverse plane of the
notch forming a locking-abutment for hold-
ing the knuckle closed and a spring inter-
posed between the pin and draw-head for
automatically turning the pin on its longi-
tudinal axis into locked position, substan-
tially as described.

6. The combination with the draw-head
having the aperture therein and the knuckle
journaled in said draw-head to move in a

plane at right angles to the aperture and having the wing or extension, of the locking-pin having the notch or recess through which the wing passes when the knuckle is opened, 5 the body of the pin in the transverse plane of the notch forming a locking-abutment for holding the knuckle closed, a spring interposed between the pin and draw-head for automatically turning the pin on its longitudinal axis into locked position and the operating-arm connected with the end of the pin; substantially as described.

7. The combination with the draw-head having the aperture therethrough and the knuckle journaled to rotate in said head in a 15 plane at right angles to said aperture and having the locking wing or extension, of the locking-pin journaled in an aperture in the

draw-head, held against longitudinal movement and having the recess through which 20 the extension or wing on the knuckle passes, the pin forming an abutment when turned in front of said wing to lock the knuckle in closed position and a stop for limiting the rotation of the pin; substantially as described. 25
